UNITED STATES PATENT OFFICE.

NAPOLEON DEMERS, OF SHERBROOKE, QUEBEC, CANADA.

BOBBIN-BORING MACHINE.

1,031,108.

Specification of Letters Patent.

Patented July 2, 1912.

Application filed February 21, 1912. Serial No. 679,090.

To all whom it may concern:

Be it known that I, NAPOLEON DEMERS, a subject of the King of England, residing at Sherbrooke, in the Province of Quebec, 5 Dominion of Canada, have invented certain new and useful Improvements in Bobbin-Boring Machines; and I do hereby declare the following to be a full, clear, and exact description of the invention, such as will 10 enable others skilled in the art to which it appertains to make and use the same, reference being had to the accompanying drawings, and to the letters and figures of reference marked thereon, which form a part of 15 this specification.

This invention relates to new and useful improvements in apparatus for boring and reaming warp and filling bobbins and comprises a simple and efficient apparatus of 20 this nature having various details of construction and combinations and arrangements of parts which will be hereinafter fully described, shown in the accompanying drawings and then specifically defined in the 25 appended claims.

I illustrate my invention in the accompanying drawings, in which:

Figure 1 is a front view of my invention. Fig. 2 is a rear elevation. Fig. 3 is a top plan view. Fig. 4 is a side view of the kickout device. Fig. 5 is a sectional view on line 5—5 of Fig. 1. Fig. 6 is a detail view of the automatic tripping mechanism. Fig. 7 is a detail view of the bobbin holder. Fig. 35 8 is a detail view of one of the bobbins. Figs. 9 and 10 are detail views of parts of the apparatus. Fig. 11 is a sectional view through one of the bobbins after having been bored by my apparatus. Fig. 12 is a detail view of a spring-pressed pivotal hook designed to prevent the endless carriage from travel in one direction. Fig. 13 is a detail view in elevation. Fig. 14 is a perspective view of an automatic feeding device, and 45 Fig. 15 is a front elevation of said modification.

Reference now being had to the details of the drawings by numeral, 1 designates the frame of the apparatus which has a metallic 50 top 2 held securely to the frame by means of bolts 3. Journaled in suitable bearings 4 are the shafts 5 and 5', upon each of which is a pair of flanged wheels 6. A driving wheel, designated by numeral 7, is fixed to a shaft 55 7', and 8 is a belt passing about the same

and adapted to be driven from any source of power and forming means for driving the apparatus. An endless carrier made up of pivotal plates, each designated by numeral 9 and one of which is shown clearly in Fig. 6 of the drawings, travels about the flanged wheels 6 and each of said plates is provided with integral eyes 10 upon corresponding edges and each carries adjustable rods 11 with eyes 12 at one end and threaded at 65 their outer ends. The rods pass through registering apertures in the plates and are held in adjusted positions by means of the nuts 13, as shown clearly in Fig. 6 of the drawings. By the provision of these adjusting features, it will be noted that any wear which may come upon the chain made up of the pivotal plates will be readily taken up.

Fixed to each plate 9 is a spindle receiving 75 bracket member 14 having a tapering recess or socket 15 therein, designed to receive one end of the bobbin 16 to be longitudinally bored. Each plate also carries, at the end opposite to that on which the socket member 80 14 is mounted, a bracket member 17, having lugs 18 rising therefrom, each provided with an aperture. Said bracket members 14, it will be noted, have upright portions which are apertured as at 14' and rods 18' pass 85 through the registering apertures in the bracket members carried at the opposite ends of the plates.

Mounted upon each pair of rods 18', it being noted that each plate carries two of 90 said rods, are the bobbin-receiving heads 19, which are shown in detail in Figs. 9 and 10 of the drawings. Each head 19 has a series of inclined fingers 20 projecting therefrom which have sharp knife edges and are designed to engage frictionally one end of a bobbin in the manner shown clearly in Fig. 3 of the drawings to hold the same in the socket member 15. Each bobbin receiving head 19 is provided with a shank portion 21 95 held adjustably by means of a set screw 22 in the bracket member 23, a detail of which is shown in Fig. 10 of the drawings, and which has laterally extending arms 24 apertured at 25 for the reception of the rods 18' 100 upon which they are mounted. Set screws 24' pass through threaded openings in said arms and are adapted to engage the rods 18' to hold said bracket members 23 in adjusted 105 positions. Coiled springs 26 are mounted 110

upon the rods 18' and have corresponding ends fastened to the bracket member 23. Said springs are also fastened to the bracket member 14 so that, as longitudinal movement is imparted to the rods 18' to the right, the springs will be under tension and will serve to return the rods to their normal positions.

Mounted to have a longitudinal, reciprocating movement upon the frame is a series of carriages, shown in rear elevation in Fig. 2 of the drawings and designated respectively by numerals 28, 29 and 30. Each of said carriages has its opposite edges grooved and adapted to receive a rib 31 to guide the carriage in its back and forth movement. Guide ribs 32 adjustable by screws 33 mounted in threaded apertures in the frame, engage respectively the outer edges of the side carriages 28 and 30. The carriage 28 bears the bit shafts 34 and 35, bit sockets 37 and 38 and bits 39 and 40. The carriage 29 bears the bit shafts 41, 42 and 43, suitable bit sockets and the bits 44, 46 and 47. The carriage 30 bears the single bit shaft 48, the socket 49 and a reamer 50. Each bit shaft carries a pulley 52 to accommodate belts 53, for which there are also overhead pulleys not shown but which have a swinging movement on suitable hangers to allow for the longitudinal sliding reciprocation of the carriages.

Projecting from the under surface of the carriage 28 is a lug 28' upon which a roller 54 is journaled and upon a lug 29' of the carriage 29 is mounted a similar antifriction roller 55, and upon the carriage 30 is a lug 30' having an anti-friction roller 56.

Journalized in suitable bearings 57 upon the frame and as shown clearly in Fig. 2 of the drawings are the three shafts, designated respectively 58, 59 and 60, to which respectively are fixed the cylinders 61, 62 and 63. Each of the cylinders is provided with two spirally shaped ribs 64, shown in Figs. 3 and 5, and it will be noted upon reference to said figure that the meeting ends of said ribs overlap each other and are spaced apart and the adjacent edges of said ribs are parallel for a short distance in order to allow the cylinder to cease momentarily the feeding movement of the carriage at a predetermined moment while the spindles are being advanced one step in the operation of the apparatus. The shaft 58 has a gear wheel 65 fixed thereto which is in mesh with a similar gear wheel 66 upon the shaft 59, and 67 is a gear wheel upon the shaft 60 intermeshing with the gear wheel 66, and a pinion wheel 68 is fixed to the shaft 7' upon which the driving wheel 7 is mounted, thereby affording means whereby the power may be applied to drive the various cylinders in the directions indicated by the arrows thereon.

Mounted upon and adapted to rotate with the shaft 5 is a star wheel 70, a pawl 71, shown in Fig. 2 of the drawings, being pivotally mounted upon a pin 72 carried by the arm 73 upon the frame and serving to hold said star wheel from rotation in one direction.

Fixed to the disk 74, which is mounted upon and rotates with the shaft 59, is an arm 75 having an anti-friction roller 76 at its free end which, at every revolution of the disk, is adapted to contact with one or another of the fingers of the star wheel for the purpose of imparting an intermittent movement thereto, sufficient to cause the bobbin to travel from the position in alinement with one bit to a position in alinement with the next adjacent one.

In order to hold the bobbins securely while being operated upon by the bits, I provide the following mechanism, illustrated in Fig. 12 of the drawings and consisting of the spring-actuated hook 76' mounted upon a pivot 77, upon the frame and which lever has one end thereof connected to the shaft 5' by a coiled spring 78. As the chain advances in one direction, the free end of the hook coming in contact with one or another of the plates of the endless carrier will be depressed to allow the plate to pass over the hook portion, after which the spring will throw the hooked end up against the edge of the plate. Simultaneously with the hook springing back against one edge of the plate, the endless carrier, made up of the plates pivoted together, will come to rest and the carriages containing the bits, which are continuously rotated by the belted connections, will be fed forward in the manner shown and described.

Mounted to have a longitudinal movement upon the carriage carrying the rotatable bit carrying shafts 34 and 35 is a rod 34' upon which are mounted the collars 35' and 36', the former being held by a set screw 110 behind the bearing blocks 36 in which the rear ends of the shafts 34 and 35 are held, while the other is in advance of the bearing blocks in which the forward ends of the bit carrying shafts 34 and 35 are journaled. The forward end of the rod 34' has a cam-shaped edge 87 adapted to be moved frictionally in contact with one of the lugs 80, shown in dotted lines in Fig. 6 of the drawings, projecting from the lower surfaces of the plates 9 to hold the endless carrier rigidly while it rests and while a bobbin is being bored. It will be noted that, at each forward longitudinal movement of the rod, 34', the cam edge thereof will come into contact with the projection 80 and hold the plate upon which a bobbin is mounted from movement in one direction, while the spring-pressed hook before described will engage the opposite edge, thus securely holding the 130

carrier momentarily while the bits are fed forward with the view of boring a longitudinal hole therein.

A tread member, designated by numeral 5 81, is pivotally mounted upon a pin 82, shown in Fig. 1 of the drawings, and a bar 83 is pivotally connected to the shank portion of the tread member and has a weighted member 84 mounted thereon. The upper 10 end of said rod 83 is pivotally connected by a pin 85 with an angle lever 86, pivoted upon a pin 86', and which angle lever has a transverse plate 87' secured thereto adapted, when the tread member is depressed, to contact with the ends of two of the rods 18' 15 mounted upon one of the plates of the endless carrier for the purpose of throwing the socket member 19 back to receive the end of a bobbin to be adjusted upon the plate. 20 When pressure is removed from the tread, the weight will tend to return the transverse plate 87' to its normal position.

The detailed mechanism for releasing the bobbin after the bore of three different diameters has been formed therein is shown in Fig. 4 of the drawings and in which I have illustrated a bar 88 which is fastened to the carriage 30 and has an aperture at one end to receive the rod 89, threaded at 90 to receive the nuts 91 and 92, provided for adjustment to limit the longitudinal movement of said rod 89. The forward end of the rod 89 is pivotally connected at 93 with one end of the lever 94 which passes 35 through a slot 95 in the bar 96. The bar 97 is fastened to the frame of the apparatus and the lever 94 is pivotally connected therewith through the medium of the link 98. The bar 96 is provided with a cross 40 plate 99 at one end thereof, which is of sufficient length to come opposite and contact with the adjacent ends of two of the rods 18', which pass through the apertures in the plates upon the endless carrier. An angled 45 rod 100 is mounted upon a pin 101 upon the bar 96 and is connected by means of a spring 102 with the bar member 97 and, when the carriage moves forward, the angled rod 100 will assume the position 50 shown in dotted lines in Fig. 4 and in its movement the spurs 103 at the end of said angled rod will engage the bobbin and remove the same from the socket.

In Figs. 14 and 15, I have shown a mechanism for feeding bobbins automatically from the hopper to the endless carrier, in which the hopper is designated 105, to the bottom of which are fastened resilient hook fingers 106 adapted to support a bobbin as it 60 falls from the hopper and which bobbin is automatically gripped by the socket member 107 and centering member 108 and fed forward by the carrier. The bobbin is gripped by the following mechanism: 65 Bearing members 107' are provided with

apertures for the reception of the sliding rods 110 and said bearing member 107' carries the socket member 107. A bearing member 109 is fixed to the rods 110 and the centering member 108 is movable within the bearing member 109. A cam-shaped member 112 is adapted to be fixed to a bracket upon the frame and in the paths of corresponding projecting ends of the rods 110. As the first of the two rods carried by each member 107' comes in contact with the cam member, both rods will be moved longitudinally as each set of rods is fastened to a bearing member 109, thus causing the latter and the centering member 108 to move therewith. After the first rod passes by the cam, the second rod will still hold the centering member back to the position shown in Fig. 14 of the drawings, allowing ample time for the bobbin to fall from the hopper 80 upon the springs 106. After the second rod 110 passes by the cam, a spring 111, which is mounted upon one of the rods 110 and put under tension as the rods 110 are moved in one direction, will return the rods and the centering member 108 to their normal positions. The centering member coming in contact with the bobbin 16 will push the same into the socket member 107, thus securely holding the same as it is fed forward 95 by the carrier. It will be noted upon reference to Fig. 14 of the drawings that a cam member 112 is fixed to the frame of the apparatus and is in the path of one end of the rod 110, and, as the latter comes in contact with the cam member, the rod will be given a longitudinal movement and throw the centering head back and, after the end of the rod has passed by the cam member, the centering member will return to its normal position and grip one end of the bobbin. 100

In the operation of the modified form, it will be noted that the bobbins will fall by gravity singly upon the resilient fingers and be held until gripped and fed forward in 110 the manner described.

In operation, the operator by pressing upon the tread member will cause the cross-piece 87' to move longitudinally two of the rods 18' and throw back the socket member carrying the head 19 to allow a bobbin to be bored to be inserted with one end in the socket member 15 and its other end engaged by the fingers of the socket member 19. An intermittent motion is imparted to the carrier by means of the fingers of the inner star wheel 70' coming in contact with the lugs 80 on the under side of the plate 9, said wheel 70' being fixed to the shaft 5 which is driven by the star wheel 70, which in turn is driven 115 by means of the antifriction rollers 76 mounted upon the arm 75 coming in contact with one of the spurs of the star wheel at each revolution of the wheel carrying said arm 75. During the interval between the 120 125 130

engagements of the roller 76 with the star wheel 70 to advance the endless bobbin carrier, the bit carriages are advanced and re-treated by the cams on the revolving cylinders 61, 62 and 63, engaging with the rollers depending from the carriages. It will be noted that the first bit 39 bores a hole of a certain depth, the next bit 40 bores the hole in the same bobbin after the latter comes in alinement therewith still deeper and the third bit 44 bores through the end of the bobbin with a bore of smaller diameter than made by the bits 39 and 40. The bits 46 and 50 will extend through and clear out any ragged edges which might remain within the bore of the bobbin. The last bit 51 constitutes a reamer and is provided for the purpose of reaming out one end of the bobbin, as shown clearly in Fig. 11 of the drawings.

When a bored bobbin comes in alinement with the cross-piece 99, shown in Fig. 5 of the drawings, the bar 96 will be given a longitudinal movement through the medium of the connections with the bar 88 upon the carriage and cause the rods 18' to be moved against the tension of the springs thereon and thereby release the socket member 19 from the bobbin. Simultaneously with the imparting of a longitudinal movement to the rods 18', the spurs 103 at the end of the curved bar 100 will move down to the position shown in dotted lines in Fig. 5 and remove the bobbin from the socket 15, and, when the carriage returns to its normal position, the parts resume the position shown in dotted lines in Fig. 5.

Upon reference to Fig. 5 of the drawings, it will be noted that, by the peculiar arrangement of the spirally-arranged cams upon the cylinders, the adjacent ends of said cams overlap each other and are spaced apart, the adjacent edges of the overlapping cams being parallel for a short distance which will allow the cylinders to rotate a short distance while the carriages are at rest and, during this interval, the endless carrier will have been given an intermittent movement sufficient to advance the bobbins a distance equal to the distance between the bits. It will also be noted that, by the provision of an apparatus as shown and described, the parts are so arranged as to cause movements of the machines to be made at predetermined moments to bring the bobbins to be bored into alinement with the bits and securely hold the carrier chain while the carriages carrying the bits are driven forward and continuously rotate through the medium of the swinging belts 53 which are driven from any suitable pulleys not shown.

What I claim is:—

1. An apparatus for boring bobbins comprising an endless carrier made up of a series of plates pivoted together, a fixed and

a spring-pressed bobbin holding member mounted upon each plate of the carrier, means for moving the spring-actuated member to receive the end of a bobbin, a series of longitudinally movable carriages, rotatable bit carrying shafts upon the latter, means for giving an intermittent movement to the carrier, mechanism for reciprocating the carriages to cause the bits carried thereby to bore holes in the bobbins while the carrier is at rest and afterward return the bits to their normal positions, a spring-actuated, pivotal hook mounted upon the frame and adapted to engage one edge of a plate of the carrier to hold the same from movement in one direction, a longitudinally movable rod having a cam edge reciprocated by the carriage, and means upon one of the carrier plates engaged by said cam edge for holding the carrier from movement in the opposite direction while a bobbin is being bored, as set forth.

2. An apparatus for boring bobbins comprising an endless carrier made up of a series of plates pivoted together, a fixed and a spring-pressed bobbin holding member mounted upon each plate of the carrier, means for moving the spring-actuated member to receive the end of a bobbin, a series of longitudinally movable carriages, rotatable bit carrying shafts upon the latter, means for giving an intermittent movement to the carrier, mechanism for reciprocating the carriages to cause the bits carried thereby to bore holes in the bobbins while the carrier is at rest and afterward return the bits to their normal positions, a spring-actuated, pivotal hook mounted upon the frame and adapted to engage one edge of a plate of the carrier to hold the same from movement in one direction, a longitudinally movable rod, 90 bearings upon one of the carriages and in which said rod is mounted, collars upon the rod forming stops to engage the parts of the carriage to cause the rod to reciprocate with the carriage, said rod having a cam edge, and a projection upon each plate of the carrier against which said cam edge is adapted to contact to securely hold the carrier from movement in one direction, as set forth.

3. An apparatus for boring bobbins comprising an endless carrier made up of a series of plates pivoted together, a fixed and a spring-pressed bobbin holding member mounted upon each plate of the carrier, means for moving the spring-actuated member to receive the end of a bobbin, a series of longitudinally movable carriages, rotatable bit carrying shafts upon the latter, means for giving an intermittent movement to the carrier, mechanism for reciprocating the carriages to cause the bits carried thereby to bore holes in the bobbins while the carrier is at rest and afterward return the bits to their normal positions, a longitudinally mov- 120

able bar mounted upon the frame, means connecting the same with the carriage and adapted to actuate the spring-pressed bobbin carrying socket to release the same from the 5 bobbin after the hole has been bored therein, a spring-pressed pivotal rod mounted upon said movable bar and adapted to push the bobbin from the fixed socket after the spring-pressed socket member has been moved out 10 of engagement with the bobbin, as set forth.

4. An apparatus for boring bobbins comprising an endless carrier made up of a series of plates pivoted together, a fixed and a spring-pressed bobbin holding member 15 mounted upon each plate of the carrier, means for moving the spring-actuated member to receive the end of a bobbin, a series of longitudinally movable carriages, rotatable bit carrying shafts upon the latter, means 20 for giving an intermittent movement to the carrier, mechanism for reciprocating the carriages to cause the bits carried thereby to bore holes in the bobbins while the carrier is at rest and afterward return the bits 25 to their normal positions, a longitudinally movable bar mounted upon the frame, a cross-piece fixed to one end thereof and adapted to contact with the spring-pressed rods carrying the bobbin receiving sockets, a 30 pivotally mounted lever engaging said longitudinally movable bar, and connections between said lever and carriage, as set forth.

5. An apparatus for boring bobbins comprising an endless carrier made up of a series 35 of plates pivoted together, a fixed and a spring-pressed bobbin holding member mounted upon each plate of the carrier, means for moving the spring-actuated member to receive the end of a bobbin, a series 40 of longitudinally movable carriages, rotatable bit carrying shafts upon the latter, means for giving an intermittent movement to the carrier, mechanism for reciprocating the carriages to cause the bits carried there- 45 by to bore holes in the bobbins while the carrier is at rest and afterward return the bits to their normal positions, a longitudinally movable bar mounted upon the frame,

a cross-piece fixed to one end thereof and adapted to contact with the spring-pressed 50 rods carrying the bobbin receiving sockets, a pivotally mounted lever engaging said longitudinally movable bar, a bracket bar fastened to the carriage, having an aperture 55 therein, a rod passing through said aperture and pivotally connected to said lever, one end of said rod being threaded, and nuts adjustably mounted thereon, as set forth.

6. An apparatus for boring bobbins comprising an endless carrier made up of a series 60 of plates pivoted together, a fixed and a spring-pressed bobbin holding member mounted upon each plate of the carrier, means for moving the spring-actuated member to receive the end of a bobbin, a series 65 of longitudinally movable carriages, rotatable bit carrying shafts upon the latter, means for giving an intermittent movement to the carrier, mechanism for reciprocating the carriages to cause the bits carried there- 70 by to bore holes in the bobbins while the carrier is at rest and afterward return the bits to their normal positions, a longitudinally movable bar mounted upon the frame, a cross-piece fixed to one end thereof and 75 adapted to contact with the spring-pressed rods carrying the bobbin receiving sockets, a pivotally mounted lever engaging said longitudinally movable bar, a bracket bar fastened to the carriage, having an aperture 80 therein, a rod passing through said aperture and pivotally connected to said lever, one end of said rod being threaded, nuts adjustably mounted thereon, and a spring-pressed, pivotally mounted curved rod 85 mounted upon said longitudinally movable bar and designed to push the bobbin from the spindle after the spring-pressed socket member has released one end thereof, as set forth.

In testimony whereof I hereunto affix my signature in the presence of two witnesses.

NAPOLÉON DEMERS.
